Thomas Whiston & Sustarus Edwin Haynes.

The schedule referred to in these Letters Patent, and making part of the same, containing a description in the words of the said Thomas Whiston and Sustarus Edwin Haynes, themselves, of their improvement in the construction of baking stoves, called the portable baking stove.

To all to whom these presents shall come - Thomas Whiston, Grocer and Stove maker, and Sustarus Edwin Haynes, Tin plater, both of Roxbury, in the County of Norfolk, and Commonwealth of Massachusetts and District -

Be it known, that we, the said Whiston and Haynes, have invented, made, constructed, and applied to use a new and useful improvement in the construction of baking stoves, which we denominate the portable baking stove - which said invention and improvement we specify, and describe as follows, namely,

The drawing hereto annexed contains a delineation of our said improvement. Figure numbered A. represents a perspective view thereof. Figure numbered B. represents a sectional view of the same. Figure numbered C. represents the grate herein after described. The same letters in the different figures represent the same parts as far as they are the same. A. A. A. represents the body of the stove. B.B.B. represents the legs by which the stove is supported. C. represents the door of the oven. D.D.D. is the top of the lower chamber. E.E. are bars placed across each end of the oven, upon which bars may be placed either long or short of the oven upon which charcoal or coal may be placed while cooking. F.F. are hollow pipes for conveying the heat and smoke from the lower chamber, into the upper chamber. G. is the door of the stove. H.H. are the handles connected with two doors, J.J. which are used to prevent, as may be required, the heat

from wood burning into the upper chamber. K. K. is the upper chamber. L. L. an opening in which bowls are to be placed and are figured numbered. M. M. is ports into & to be placed in some of them. M. represent the Yarnell through which the smoke escapes. N. N. represents pieces of sheet iron or other suitable material, placed in the oven: perpendicular against said pipes and fastened thereto by means of projections or flanges used to prevent the heat from striking so suddenly in the food while cooking, and to diffuse the heat over the oven. O. is a fence of sheet iron or other suitable material, placed near the top of the lower chamber and riveted or fastened to the sides of the chamber to prevent the heat from striking too suddenly against the bottom of the oven, and to cause the oven to be heated more uniformly. P. is the handle connected with the grate. Q. Q. which contains the fire. The grate is composed of cast iron with bars, a. a. placed in the bottom sufficiently near each other to prevent the fire from falling through, and yet to permit the ashes to escape. The grate is rectangular and has four legs. A. A. upon which it is supported. On the front third is an opening R. R. to allow of a draft of air, with the exception of the draft above named, the whole grate is made to fit into the receiver or pan S. S. which is placed underneath the body of the stove, and nearly in the middle thereof, and is used to receive the ashes from the coal or wood. The receiver or ash pan by means of flanges c. c. is fastened to the bottom of the body of the stove. There is also an aperture in the bottom of the stove directly over the place where the receiver or ash pan is fastened thereto, and communicating with the lower chamber. This aperture is about half the whole length of the grate from the side of the stove. The body of the stove may be cylindrical, cubical, rectangular or oval, and of any convenient size. It may be made of sheet iron or polished tin, or other suitable materials, no preference being had to tin. The ordinary size which would be required is twenty four

which long, fourteen wide, and fourteen high. The legs are of iron or other suitable material, and are joined across the bottom of the stove, and are to give strength and form to it, and are about two inches long. The interior or back part of a stove of the dimensions before named is nine and one quarter inches long, and five and one quarter wide, and five and one half deep, and is placed as near as may be in the centre of the bottom of the stove, so that the mouth thereof shall be nearly even with the fronts of said stove. In larger or smaller sizes it should be made in proportion. It is made of stiff sheet iron or other suitable material. The grate is of cast iron, and for a stove of the above size should be made nine inches long, five wide, and three and a half deep, and resting on four legs or supports, and when placed within the interior or pan, should be made with the exception of the opening, for a draft to close the whole front of the pan. The bottom chamber occupies the whole space between the bottom of the oven and the bottom of the stove, excepting that a very small space about one inch wide, may be left in the front and rear of the oven. For the purpose of fastening it to the bottom of the stove. The lower chamber in the size above named is two and one half inches deep. The oven occupies the whole space between the two chambers excepting what is occupied by the two pipes. This is ten inches deep. Any number of bars may be placed across each end of the stove that may be required, and on these other bars are laid lengthwise of the oven on which the food required to be cooked is placed. The pipes pass from one chamber to the other, and may be either cylindrical, oval, or of any other suitable shape. We prefer those that are oval, as we think they occupy less space, and in other respects answer the purpose equally well. In the sizes before mentioned the pipes are four inches ^{diameter} and ten inches long. The upper chamber occupies all the space between the tops of the

oven and the top of the stove, and on the size I have mentioned, is about two and a half inches high. The fender is half an inch wide, inches wide and extends only to the top of the pipes to which they are fastened. The fender O. which prevents the heat from coming directly against the bottom of the oven is four and a half inches wide, and ten inches long, and is fastened at each end to the sides of the oven, the ends being turned up so as to leave a space between it and the bottom of the oven. The dampers are made of sufficient size, and are so constructed and placed in the upper chamber as when closed to cover entirely the two pipes. The opening for the boiler are about nine inches in diameter in a stove of the size above described, and when one is fastened over the opening and stopped by a shot iron or other covering, and when the stove is not wanted for boiling, it may be made without the opening. The smoke pipe is about four and a half inches in diameter. The door of the oven is fifteen inches long, nine and a half inches high, and is made to turn at angles, and to close entirely the mouth of the oven. The aperture in the bottom of the stove is four and a half inches wide, and six inches long. We do not however restrict ourselves to the particular dimensions herein before named; we believe however, that for the size mentioned, the different parts are well proportioned, and that they should be made larger or smaller, according to the size of the stove to be used. When the stove is made of polished tin, or other polished material, it retains almost all the heat within itself, but when made of shot iron, or other material not polished, the heat passes off, and would soon extinguish the apartment in which it is placed. The different parts of the stove are put together by means of nuts or screws in such a manner that the heat will not affect them. No wood stove is calculated for the burning of charcoal, bituminous or anthracite coal or wood, when the latter is used

the grate is air-tight with and a door with a suitable flueing
for a draft may be used to close the incinerator or Ash-pans. The coal
is placed in the grate, and the heat and smoke produced by the
burning thereof passes through the apertures in the bottom of the
stove, and the heat strikes against the fender O and fender
is radiated and diffused over the whole of the surface of the
lower chamber. The fender O is placed only directly over the
grate and is open on both sides, so as to permit the heat to
pass between it, and the top of the lower chamber. This will
produce sufficient heat to bake or cook any articles of food
placed in the oven, and will produce an uniform heat,
so that the food will be baked or cooked uniformly throughout.
The smoke and heat also pass from the lower chamber through
the pipes, nearly over the two pipes are placed the openings
for the boilers. These openings are placed a little nearer
the smoke pipe, than the two pipes, because the smoke
and fire are rushing towards the funnel to escape. The
object of the dampers, is to permit all the smoke and heat
from the fire to pass under one boiler, when only one is
required, or by shutting both after the fire has burnt down
to retain the whole heat. The smoke and waste heat are carried
off in the smoke pipe, which by means of a common fan
may be made to communicate with a chimney or the
open air.

Although we have described the different parts of
the said stove, yet we do not claim the different parts thereof
separately as new but what we claim as new and our inno-
vation and discovery, is, the construction and arrangement of
the whole of said stove, and its different parts in the con-
nection and combination, and for the purposes aforesaid —

I testify that the above is a true specification
of our said improvement as above described. We have hereto

Set our hands, this thirtieth day of November in the
year of our Lord One thousand eight hundred and
thirty four.
